BY *J. H. Cook*
ATTORNEY

UNITED STATES PATENT OFFICE

STEPHEN S. ADAMS, OF ST. LOUIS, MISSOURI

FASTENING DEVICE

Application filed January 10, 1931. Serial No. 507,806.

This invention relates generally to light-reflecting signs of the type including the use of cataphotes, or light-reflecting buttons which reflect rays of light directed there-
 5 upon by automobile headlights and the like, for the purpose of illuminating the signs, and more particularly to an improved fastening device for securing said cataphotes or light-reflecting buttons in place in the signs, the predominant object of the invention being to provide an extremely simple fastening device of the type referred to which is so constructed and arranged in the signs that the cataphotes or light-reflecting
 10 buttons may be very easily introduced in place and fastened therein in a very secure manner.

Prior to this invention much inconvenience and annoyance was occasioned in connection with the maintenance of light-reflecting signs of the type referred to above, due to the absence of an entirely successful means for securing the cataphotes or light-reflecting buttons in place in the signs. In the case of
 25 some of the signs heretofore used, the cataphotes or light-reflecting buttons were unattached to the signs and were held in place merely by contact with the removable rear walls thereof. The result of this arrangement was that when the rear walls of the signs were removed for any purpose, the cataphotes or light-reflecting buttons would fall out of place.

Other means for securing the cataphotes or light-reflecting buttons in place were adopted heretofore, but none of such means were found to be entirely successful in use.

In view of the foregoing, I have devised the fastening device disclosed herein, which, 40 briefly stated, comprises a yoke-like structure which is connected to the front wall of the sign and embraces the rear portion of the associated cataphote or light-reflecting button. The fastening device is so arranged that it is capable of pivotal movement with respect to the front wall of the sign, such movement providing for the fastening device being moved to a position where the associated cataphote or light-reflecting button
 45 may be readily introduced into place, where-

upon the fastening device may be moved to a position where it embraces the rear portion of the cataphote or light-reflecting button and thus securely holds same in place.

Fig. 1 is a fragmentary front elevation of 55 a light-reflecting sign which is provided with my improved fastening devices for securing the cataphotes or light-reflecting buttons thereof in place.

Fig. 2 is a horizontal section on line 2—2 60 of Fig. 1 showing a cataphote and one of my improved fastening devices in elevation.

Fig. 3 is a fragmentary rear elevation illustrating the rear portion of one of the cataphotes or light-reflecting buttons and showing 65 one of my improved fastening devices in use.

Fig. 4 is an enlarged section on line 4—4 of Fig. 1 showing a cataphote and one of the improved fastening devices in elevation. 70

Fig. 5 is a modified form of the improved fastening device.

Fig. 6 is still another modified form of the invention.

In the drawing, wherein are shown for the 75 purpose of illustration, merely, several embodiments of the invention, A designates a fragment of the front wall of a light-reflecting sign, said front wall preferably being provided with a depressed portion B which 80 is shaped to provide a letter of the complete sign. The front wall A of the sign is provided with a plurality of apertures C formed therethrough which are arranged in a configuration corresponding to the shape of the 85 letter produced by the depressed portion B, and as shown clearly in Fig. 1 each aperture C is circular in shape and is provided at its opposite sides with notches C'.

Partially extended through each of the 90 apertures C is a cataphote, or light-reflecting button D, said cataphote or light-reflecting button comprising a body portion D^a and an enlarged head portion D^b, the latter portion being covered by a metallic shell E. The outer end portion of the body portion of the cataphote or light-reflecting button D is rounded, as shown clearly in Fig. 4, and this rounded end portion is extended through the 95 associated aperture C in the front wall of the 100

sign. Also, the body portion D^a of each of the cataphotes or light-reflecting buttons D is tapered from a smaller diameter at its forward portion to a larger diameter at its rear portion, and said tapered diameter is of such size relative to the size of the associated aperture C that the cataphote or light-reflecting button seats against the wall of the aperture C , whereby excessive forward movement of the cataphote with respect to the front wall A of the sign is prevented.

My improved fastening device comprises a substantially **U**-shaped element F having outwardly turned gripping portions 1 at the outer ends of the leg portions 2 . Also, the fastening devices F each include a bridge portion 3 which joins the leg portions 2 thereof, as shown in Fig. 2. Each fastening device is preferably in the form of a one-piece or integral structure formed of resilient material, and the bridge portion 3 , as shown in Fig. 2, is preferably bowed and is provided with curved portions 4 at opposite sides thereof which join the bowed bridge portion 3 with the leg portions 2 . By providing the fastening device with the curved portions 4 the resiliency of the device is greatly increased, whereby the fastening device may elongate and thus adjust itself to different positions of the associated cataphote. Also, this resilient arrangement of the fastening device provides for the use thereof with cataphotes of different sizes and shapes. In addition to the resiliency imparted to the fastening devices by the curved portions 4 , the bowed condition of the bridge portions 3 adds to the resiliency of the device. Preferably the bridge portions 3 of the fastening devices are each provided with an enlarged portion $3'$ adapted to contact with the rear face of the associated cataphote or light-reflecting button.

In the use of one of my improved fastening devices, the outer end portions of the leg portions 2 thereof are extended through the associated aperture C , as shown most clearly in Fig. 2, in a manner to cause the outwardly turned gripping portion 1 to contact with the outer face of the front wall A of the sign. When viewed in cross-section, the outwardly turned gripping portions 1 are of arcuate formation, as shown in Fig. 4, and this arrangement permits of the fastening device being subjected to pivotal movement, the arcuate face of the gripping portions 1 functioning in very much the same manner as a round pivot pin. When the fastening device is arranged with the outer portions of the leg portions thereof extended through the associated aperture C , as described, said leg portions are disposed in the notches C' at opposite sides of the aperture, and because the depth of the notches approximately equals the thickness of the leg portions as shown in Fig. 1, the full diameter of the

aperture is maintained throughout. In other words, the leg portions of the fastening device do not project into the aperture C , for if this were so said leg portions would interfere with the proper location of the associated cataphote or light-reflecting button in said aperture.

In arranging a cataphote or light-reflecting button D in place in the sign, the fastening device F is moved to the position in which same is illustrated by dotted lines in Fig. 4, the notches C' being of sufficient length to permit such pivotal movement of the fastening device. The cataphote or light-reflecting button D is then arranged in position with its forward rounded portion extended through the associated aperture C , as shown in Fig. 4, after which the rear end portion of the fastening device is moved, by being pivoted about the gripping portions 1 , to the position in which it is shown in full lines in Fig. 4. The fastening device is resilient so as to be capable of elongation, as already explained, hence said fastening device will yield as it is moved in contact with the rear end of the cataphote or light-reflecting button D . Also, because of this resiliency, the tapered face of the body portion of the cataphote or light-reflecting button will be forced firmly into contact with the wall of the aperture in a manner to securely hold said cataphote or light-reflecting button in place. When it is desired to remove a cataphote or light-reflecting button from a sign, it is necessary to merely subject the fastening device to pivotal movement so as to move said fastening device to a position where the cataphote or light-reflecting button may be withdrawn from the associated aperture, after which the leg portions 2 of the fastening device may be moved toward each other to permit removal of the gripping portions 1 through the aperture.

In Fig. 5 I illustrate a slightly different form of the invention in accordance with which the desired resiliency is imparted to the fastening device by providing the bridge portion $3''$ thereof with a curved portion 5 .

The fastening device illustrated in Fig. 6 is provided with a plurality of bowed or curved portions $4'$ at each side thereof for giving the device the required resiliency instead of a single one of such portions at each side, as illustrated in the preferred form of the invention.

I claim:

1. A device for fastening a light-reflecting element in place at an opening in a wall of a sign comprising a yoke-like element including leg portions and a bridge portion, and outwardly extended gripping portions arranged at the outer ends of said leg portions, said leg portions being adapted to be extended through said opening in said wall of said sign in a manner to cause said out-

- wardly extended gripping portions to contact with the face of said wall of said sign, and said bridge portion being adapted to engage said light-reflecting element in a manner to 5 secure same in place.
2. In combination with a sign including a wall provided with an aperture formed therethrough and a light-reflecting element disposed at said aperture, a fastening device for 10 securing said light-reflecting element in place, said fastening device comprising a yoke-like element including leg portions and a bridge portion, and outwardly extended gripping portions arranged at the outer ends 15 of said leg portions, said leg portions being extended through said aperture in said wall of the sign in a manner to cause said outwardly extended gripping portions to contact with a face of said wall.
- 20 3. In combination with a sign including a wall provided with an aperture formed therethrough and a light-reflecting element disposed at said aperture, a fastening device for securing said light-reflecting element in 25 place, said fastening device comprising a yoke-like element including leg portions and a bridge portion, and outwardly extended gripping portions arranged at the outer ends 30 of said leg portions, said outwardly extended gripping portions being provided with curved faces and said leg portions being extended through said aperture in said wall of the sign in a manner to cause the curved faces 35 of said outwardly extended gripping portions to contact with a face of said wall so as to facilitate pivotal movement of the fastening device with respect to said wall of the sign, said yoke-like element being provided with portions shaped to impart resiliency thereto.
4. In combination with a sign including a 40 wall provided with an aperture formed therethrough and a light-reflecting element disposed at said aperture, a fastening device for securing said light-reflecting element in place, said fastening device comprising a 45 yoke-like element including leg portions and a bridge portion, and outwardly extended gripping portions arranged at the outer ends of said leg portions, said outwardly extended gripping portions being arcuate in cross-section 50 so as to be provided with curved faces and said leg portions being extended through said aperture in said wall of the sign in a manner to cause the curved faces of said outwardly extended gripping portions to contact 55 with a face of said wall so as to facilitate pivotal movement of the fastening device with respect to said wall of the sign.
5. In combination with a sign including a 60 wall provided with an aperture formed therethrough and a light-reflecting element disposed at said aperture, a fastening device for securing said light-reflecting element in place, said fastening device comprising a resilient yoke-like element including leg portions and a bridge portion, and outwardly 65 extended gripping portions arranged at the outer ends of said leg portions, said outwardly extended gripping portions being provided with curved faces and said leg portions being extended through said aperture in said wall of the sign in a manner to cause the curved faces of said outwardly extended gripping portions to contact with a face of said wall so as to facilitate pivotal movement of the fastening device with respect to said wall of the sign.
6. In combination with a sign including a 70 wall provided with an aperture formed therethrough and a light-reflecting element disposed at said aperture, a fastening device 75 for securing said light-reflecting element in place, said fastening device comprising a yoke-like element including leg portions and a bridge portion, and outwardly extended gripping portions arranged at the outer ends of said leg portions, said outwardly extended gripping portions being provided with curved faces and said leg portions being extended through said aperture in said wall of the sign in a manner to cause the curved faces of said outwardly extended gripping portions to contact with a face of said wall so as to facilitate pivotal movement of the fastening device with respect to said wall of the sign.
7. A device for fastening a light-reflecting element in place at an opening in a wall of a sign, comprising a yoke-like element including leg portions having gripping portions at their outer ends and a bridge portion, said gripping portions being adapted to be extended into said opening and to engage portions of said sign, and said leg portions and said bridge portion being adapted to embrace said light-reflecting element in a manner to secure same in place.
- In testimony that I claim the foregoing I hereunto affix my signature.
